Primary Examiner — Karen S Acker*Assistant Examiner* — Steven B Reinholdt, Jr.(74) *Attorney, Agent, or Firm* — Polsinelli PC(57) **CLAIM**

The ornamental design for a lid for bottle, as shown and described.

DESCRIPTION

FIG. 1 is a perspective view of the lid for bottle;

FIG. 2 is a lower perspective view of the lid for bottle;

FIG. 3 is a front view of the lid for bottle;

FIG. 4 is a rear view of the lid for bottle;

FIG. 5 is a right side view of the lid for bottle;

FIG. 6 is a left side view of the lid for bottle;

FIG. 7 is a top view of the lid for bottle; and,

FIG. 8 is a bottom view of the lid for bottle.

The broken lines and the areas within them shown in the figures depict portions of the lid for bottle that form no part of the claimed design. The dot-dash-dot broken lines depict the boundaries of the claim and form no part thereof.

1 Claim, 5 Drawing Sheets(56)
